UNITED STATES PATENT OFFICE

120,885

DESIGN FOR SUNGLASSES

Jack Galter, Chicago, Ill.

Application March 9, 1940, Serial No. 90,788

Term of patent 3½ years

To all whom it may concern:

Be it known that I, Jack Galter, a citizen of the United States of America, residing at 711 West Lake Street, Chicago, Illinois, have invented a new, original, and ornamental Design for Sunglasses, of which the following is a specification, reference being had to the accompanying drawing, forming a part thereof.

Fig. 1 is a front view of the front frame only of a pair of sunglasses showing my new design; Fig. 2 is a rear view of my sunglasses with the temples in place, Fig. 3 is a side view and Fig. 4 is a top plan view of the same.

I claim:

The ornamental design for sunglasses, substantially as shown.

JACK GALTER.
